METHOD OF MAKING METAL PARTS FOR
RING BINDERS

John Schade, Holyoke, Mass., assignor to National Blank Book Company, Holyoke, Mass., a corporation of Massachusetts

Application December 20, 1943, Serial No. 514,920

5 Claims. (Cl. 140—88)

This invention relates to improvements in the method for making ring binders. It is customary in making ring binders to provide binder rings held in and forming part of a toggle frame construction. The frame usually carries the binder rings and operates under pressure from a spring plate to hold the rings open or closed according to the position into which the toggle frame is moved by hand against the spring pressure. Ordinarily the elements of such construction are each separately made to their individual and final form and then the separate elements are assembled to make the form of their combination. This ordinary way of manufacture requires a lot of work, particularly in the assembly of the elements after they have been separately formed. And it necessitates a certain amount of fitting together by adjustment of parts which slows down the assembly work.

An object of my invention is to permanently assemble most of the material entering into such a combination before the material is all formed into the shape for the separate individual elements, to then give the desired shape to the material for such elements, and by most conveniently arranged method steps make them ready for quick assembly with the spring plate to provide the finished construction of the combination or ring binder mechanism. Another object is to provide a form of ring and frame structure which is particularly adapted to be made by my method without complications in the desired practice of the method. Such structure is made the subject of a divisional application.

I will disclose the structure and the general plan of the method of making it and afterwards refer to particulars pertaining to the useful method steps and their order.

In the drawings

Fig. 1 shows the plan of assembling straight pieces of wire and welding their intersections;

Fig. 2 shows some of the assembled wire material with indications of a first shaping step;

Fig. 3 is like Fig. 2 with a second shaping step indicated;

Fig. 3—A is an end view of Fig. 3;

Fig. 4 is like Fig. 3 with a third shaping step indicated;

Fig. 5 is like Fig. 4 with a fourth shaping step indicated;

Fig. 5—A is an end view of Fig. 5;

Fig. 6 is a view like Fig. 5 showing a cutting and wire end shaping step;

Fig. 6—A is a side view of an end portion of Fig. 6;

Fig. 7 is a perspective view of the shaped wire

parts ready to be assembled into the spring plate;

Fig. 8 is a fragmentary side view showing the finger piece positions at the start and end operations in being bent to its final position;

Fig. 9 is a plan view of the assembled ring binder including the spring plate;

Fig. 10 is an end view showing the rings closed; and

Fig. 11 is a similar end view showing the rings in open position.

Of course the work steps indicated in the drawings will be done in commercial practice by automatic machinery. But they can be done by hand from the raw material or wire to make the finished product. So the method steps will be described without the complicated disclosure of automatic machinery.

To begin, two parallel wires 1 and 2, which may be of indefinite length, are positioned to receive 20 laid on cross wires 3. These cross wires are laid parallel on wires 1 and 2 and as shown are spaced one from the other at any desired spacing. The cross wires may be supplied from an indefinite length, laid on, and then cut for all the ends on 25 the same side to line up evenly in a straight line, or as indicated at *a* and *b* they may be laid on and successive ends cut on the same side slightly staggered, although all the cross wires 3 are of the same length. The purpose of the staggered 30 ends will be referred to later on.

When the cross wires 3 are laid on the long wires 1 and 2, their contacting points are all 35 welded together as indicated at 4. A preferred way to do this is progressively in pairs and by welding all contacting points of two cross wires to the long wires 1 at the same time by a multiple welding machine. Thus if the long wires are moved ahead intermittently the length of two spacing distances of the short cross wires, they 40 can be rapidly assembled in pairs, their ends cut off, successive pairs of short wires welded in the assembly with the long wires, and the welded assembly will then arrive in pairs of short wires at convenient stations for subsequent work steps.

45 Of course the arrangement of assembling in pairs is by way of example. One, two, or more short wires may be assembled simultaneously, I merely prefer two at a time, the example given. In this way a ladder-like assembly of long wires and short wires may be formed progressively and indefinitely continued as long as desired. This is all indicated in Figs. 1 to 5 inclusive by way of example.

50 After a pair of cross wires 3 are welded and then moved with the long wires 1 and 2, to the

next work station, their central portions between wires 1 and 2 are flattened by swaging as shown at 5 in Fig. 2. A flattened portion is preferably given the form shown best in Figs. 3 and 3-A.

After these flattened portions 5 are made, the wires move forward to the next station and the portions of cross wires 3 extending beyond or in overhanging relation to wires 1 and 2 are bent or curved into substantially semi-circular form, see portions 6 in Figs. 3 and 3-A. The overhang on one side of each cross wire 3 is bent oppositely to the overhang on the other side and together they form the complementary sides of one binder ring. If the cross wires are of a material or a size which does not bend easily at one operation, then they can be partially bent in one operation at one work station and again bent further at another station until bent the wanted amount.

After the cross wires 3 are bent to ring form, the upper ends of each wire are cut into complementary fitting forms. A preferred arrangement for such ends to be cut is shown in Fig. 4 in the two left hand rings. It is advisable to make these cut forms starting from underneath and cutting outwardly. This will avoid even the smallest size burr being left on the lower edge. Thus when the paper sheets are turned on the rings in the finished structure they will have smooth passage in contact with the under sides of the rings.

Up to this point the work is carried on while the stiff ladder-like form of wire material, seen in Figs. 1 to 4, is integral and in most convenient form for mass production steps. Now that the rings are formed and their outer ends shaped for matching fit when closed, it is desired to form toggle mechanism joints in the structure as will be explained. This is a particularly important feature of my invention.

The toggle joints are formed while the ladder-like form of wire is resting at the appropriate work station. As indicated in Fig. 5, the two left hand rings are at such a station. The work at this station is conveniently done by operations on two of the cross wire flattened portions simultaneously. The work consists in making the cut 7, see Fig. 5-A, across the flattened portion 5, at the same time making the little transverse cut 8, from the edge inwardly of one of the severed ends, and reversely bending the tongues 9 and 10 as shown best in Fig. 5-A. This bending is preferably done by the appropriate shape of a two part die cutting tool. In the product the edge on one side of cut 7 is like a knife edge, the portion 5 being flattened and thin as it is, for pivotal engagement along the line made by the root portions of the oppositely bent tongues 9 and 10. The arrangement makes a most inexpensive type of pivotal engaging parts for the ends of the ring halves and a most efficient joint between these parts. This feature will be referred to again later on. While I emphasize its advantage, the cut ends of the cross wires could be shaped in other ways for their pivotal engagement. For example, a transverse notch in one end and a transverse V-shape made on the other end would form pivotally engageable parts. But to form them that way in carrying out my method, would involve bending the cut ends up to work on them and then bending them back for the jointed position in which they function. This would be nowhere near as easy as the operations shown, as preferred, and the joint would not be as good.

After these pivotally engageable ends are made out of portions 5 for the rings, the successive steps taken to bring the ladder-like material to

the work stations will move the desired length of long wires with the severed and formed cross wires past the last forming work station. Then a desired length of the parallel long wires with the desired number of matching half rings on them may be cut off. The cut off parts are assembled with an arched spring plate as will be described.

In the final assembly it is sometimes desirable to have a ring opening device at one end, as I have indicated in Figs. 10 and 11. It consists of two bent up ends 11 and 12 of the long wires 1 and 2. These are crossed as shown. By pressing these as finger pieces in the direction of the arrows, the rings are easily opened.

Such an opening device is preferably provided for in my method steps as follows: In arranging the method steps to be carried out at successive stations, one of the first steps is to feed the cross wires on the long wires. The latter are moved forward step by step, the cross wires are fed on. When enough wires have been fed on to provide for one binder mechanism of desired length and number of rings, the feed of the cross wires may be interrupted to permit the advance of the needed lengths of the long wires, free of cross pieces, for forming the finger pieces for the ring opening device. The spacing as shown is by way of example and of course no welding or forming operations are performed along the bare lengths of the long wires from which the finger pieces are to be formed. At the cutting off station 13, Fig. 6, the cutting is delayed until the bare portions of the long wires which are to form the finger pieces have passed the cutter as shown in the latter figure. Alternatively, of course, the cutting could be timed so as to be made in the normal position behind the last ring of the preceding ring assembly so that the bare portions of the long wires project from the forward end of the assembly still being worked on. In the manner of cutting illustrated, the bare portions are bent up at the cut off station in the positions best shown in Fig. 6-A. Their hooked ends are here positioned so as not to engage. When the assembly with the spring plate 14 is made as indicated in Fig. 8 the finger piece 12 is bent toward the other one 11 so the hooked ends will engage as desired. Such an arrangement in the method makes it easier to assemble the two halves of the ring frame in the spring plate when the opening device is to be made part of the structure.

The assembly of parts with spring plate 14 is easily made. The long wires are bedded in the hook-shaped sides of the spring plate 14, with the ring halves threaded through the adjacent holes. The lower ends of the ring halves are put into pivotal engagement, each as in Fig. 11. Then the finger piece 12 is bent into final position as stated.

Considering the ring arrangement in the finished assembly Fig. 9, it will be noted that the upper ends of the ring halves 6 do not come together for their ends to meet in the same longitudinal and vertical plane. They have a staggered arrangement with respect to the meeting points, indicated at c and d. As shown, alternate rings meet in the same vertical plane and there are two planes of meeting ends. This is an advantage in the easier threading on the rings of the hole punched loose leaf sheets, particularly when the rings are closely spaced. The sheet first threads every other ring in every other hole, and this holds it in position to engage the remaining rings. When all the rings need to engage all the

holes at one time, the proper alignment is sometimes difficult to get, particularly when there are many rings and many holes to be engaged.

Such a refinement of ring arrangement is most easily incorporated in the structure by the nature of my method steps. It is only necessary to feed the cross wires 3 in the staggered arrangement on the long wires, according to the plan I pointed out before with respect to ends *a* and *b* in Fig. 1. This is done without the slightest difficulty, and the result is that the structure can be made better without any extra expense.

While I have shown long wires of round cross section, the method can be carried out also with flattened instead of round wire. The cross wires may also be made of somewhat flattened wire with the long axis parallel to the long wires. Such changes are obvious variations within my method.

There are in the prior art ring binder constructions of various kinds made by relatively expensive methods which can now be made by my inexpensive method. Choosing one of these that in some respects is similar in structural features to the structural arrangement, I have discussed above, I will refer to that of the prior art Trussell Patent #959,182. The spring plate in such construction is the same as mine except it is turned over and does not function as a cover plate. The operation is equivalent. In this prior structure the long wires corresponding to my wires 1 and 2 are flat instead of round in cross section, and the ring halves are fixed as if integral with the cross wires, as mine are. And the lower ends of the rings are held by the spring plate in pivotal engagement so as to make the same general kind of spring toggle arrangement or frame as I have described, for opening and closing the rings with the aid of the spring plate. A principal difference is in the nature of the pivotally engaging ends. But in either case my method of making could be followed to advantage in making this general type of structure. This one Trussell structure is referred to by way of example. It illustrates the fact that my method if adapted to make ring binders of a type, the mere details of which may be varied to a considerable degree. While the features of staggering the ring ends as at *c* and *d* in Fig. 9, and providing the finger pieces 11 and 12 for opening the rings have been described in detail, they are refinements in structure, mentioned to show how well adapted my method is to build in such refinements without adding any substantial cost in the making of them. They may be omitted and my method will be of large advantage in building the ring binder of the type generally referred to.

A feature of the method is that the parts will assemble and fit together in the spring plate without the need for any precision fitting. The matched ends of the ring prongs on the top have a self centering tendency. The matched ends of the toggle levers at their pivotally engaged parts are shiftable to a sufficient extent to need no precision fitting. Thus when the two halves of the frame are cut off from the longer frame they will assemble easily in the spring plate. When the halves are put anywhere near together as they are wanted in the spring plate, each half is shiftable relatively to the other and easily as a whole. Thus the ring prongs and the toggle levers can be brought into matching position without any need for any individual precision fitting anywhere in the structure. There is con-

siderable leeway available. And such leeway is important for economy and convenience in fast assembly work of such wire and sheet metal structure. Furthermore, such leeway makes a better working final product because if any part is sprung out of line a bit still the assembly is loose enough to continue all the expected operations without any cramping action of the operating parts.

It will now be clear that the type of structure shown in Fig. 7 both generally and specifically may be usefully made by my method and that its cost will be low. The method is one which is particularly well adapted to make such a structure with any desired number, size, and spacing of ring structure in toggle frame structure.

As I have said, the bent ends 11 and 12 are refinements in the structure. It will be made by my method without these bent ends. When thus made the structure seen in Fig. 7, but without the bent ends, can be conveniently made in very long lengths at the factory. Such long lengths may be divisible into many short lengths, each of a wanted binder size. There are many different sizes wanted. By keeping the long lengths in stock they can be used to supply all different sizes simply by cutting to any short length. Thus the amount of material kept in stock can be much less than when all different sizes are stocked, and still insure a supply. Furthermore, the procedure of my method fits the plan of keeping the work going without regard to particular lengths. That is to say, there need be no tie up in the factory while changing machinery from one size of binder mechanism to another in their making operations.

In my description of the method in its preferred form I have disclosed the preferred sequence for the working steps. For example, there is an advantage in maintaining the ladder-like form of material in relation to one or another work step. But it is obvious that the sequence of steps may be varied to a considerable extent without departing from the invention in its broader aspects. I have taken this into account in drawing my claims wherein some do include and some do not emphasize a particular sequence.

Having disclosed my invention, I claim:

1. The method of making the multi-prong and frame members for a loose leaf binder which consists in arranging a pair of long supporting wires in parallel spaced position, moving them lengthwise in steps, positioning one or more short spaced cross wires on the long wires between said steps, with their end portions extended at each side beyond the spaced long wires, fastening the wires as by welding at their intersections, thereby forming a ladder-like formation of wire, and between said steps forming the projecting ends of the cross wires into complementary prongs, separating their intermediate portions and forming their terminals into pivot joints, and finally cutting the long wires when the cross wires are formed as stated, whereby the two halves of each cut off formation will serve for the multi-prong members of a loose leaf binder.

2. The method for the purpose described which consists in laying out parallel long wires a fixed distance apart, feeding cross wires spaced one from another, with their end portions in overhanging relation to the long wires, fixing the cross wires as by welding to the long wires at their points of intersection, feeding the long wires lengthwise and repeatedly feeding and fixing cross wires thereon to continue building the wire material in a ladder-like formation, and

with the support from such a formation, working the wire material of each cross wire as it lies between the long wires into a separable pivotally engaging joint, shaping the overhanging portions of each cross wire into oppositely arranged complementary ring portions with complementary matching ends, doing said working and shaping of the cross wires in any desired order but before the long wires are cut, and cutting off portions of the long wires when each such portion is successively supplied with enough units of the cross wires worked and shaped as stated to serve in a binder mechanism of any chosen length and repeating these steps on the material of said ladder-like formation back of the cut-off portions to prepare additional portions for the cutting off.

3. The method of making a ring binder mechanism which consists in assembling two long straight wires in parallel spaced rail form, tying them together by parallel straight short wires, as by welding their intersections with the long wires, the short wires being spaced ring distances apart and presenting overhanging ends long enough to make complementary ring prongs, shaping the central portions of the short wires, between the long wires, into pivotally engageable and separable toggle levers shaping the overhanging portions of the short wires into complementary ring prongs with matching ends, and doing this work in steps while the short wires are fastened to both long wires as stated, at least until the ring prongs are shaped and it is necessary to cut the central portions of the short wires for completing the cut ends for said form of pivotally engageable toggle levers, then mounting each long wire with its prongs and toggle levers to match the prongs and complementary levers of the other long wire in a spring plate to complete the mechanism.

4. The method of making a ring binder mechanism which consists in fastening a pair of spaced side wires to a plurality of spaced cross wires, as by welding to make a stiff frame of ladder-like formation, the cross wires having portions extending beyond the side wires, shaping these extended portions into complementary ring holding prongs, spreading the central portions of the

5 cross wires between the side wires, carrying out such shaping and spreading steps while the frame is in a substantially integral form, cutting the cross wires at their central portions on a line parallel to the side wires, and also a short distance inwardly from one cut edge of said cross wire cut to form tongues and bending one tongue below and one above the adjacent cut edge to provide for pivotal engagement of adjacent cut edges of the cross wire portions, and finally mounting the side wires within a spring plate of a binder mechanism with the upper parts of the cross wires forming complementary prongs and the lower parts complementary toggle levers between the side wires.

5. The method of making ring binder mechanism which consists in progressively assembling wire pieces for ring elements across a pair of parallel spaced wire material of long indefinite length for the side wires of toggle frames, the cross wire pieces being spaced ring distances apart, fastening the wire pieces, as by welding, to the side wires to make a stiff ladder-like frame assembly, the cross pieces in the assembly overhanging the side wires far enough to furnish material for bending ring prongs in complementary pairs out of each cross piece, the side wires being spaced enough to bound a cross piece section long enough to furnish material for two toggle levers, and progressively working the material as furnished in said frame assembly into curved matching ring prongs from the overhanging portions of the cross pieces and into separate, matched end, toggle pivotally engageable levers, from the portions of the cross pieces between the side wires of the frame, and while thus working the frame parts into the said forms maintaining the frame part uncut until necessary to finally form the separate toggle levers and then cutting the frame apart progressively at the cross pieces, as such toggle levers are to be finally formed, and progressively cutting the frame at the side wires only when enough work has been done to furnish a length desired for at least one binder mechanism and finally assembling the halves of the frame part thus cut with a spring plate for a ring binder mechanism.

JOHN SCHADE.
